UNITED STATES PATENT OFFICE.

ADRIAN J. NEERKEN, OF DETROIT, MICHIGAN, ASSIGNOR TO PACKARD MOTOR CAR COMPANY, OF DETROIT, MICHIGAN, A CORPORATION OF MICHIGAN.

DESIGN FOR A VEHICLE-BODY.

45,722.

Specification for Design.

Patented May 5, 1914.

Application filed March 22, 1913. Serial No. 756,226. Term of patent 7 years.

To all whom it may concern:

Be it known that I, ADRIAN J. NEERKEN, a citizen of the United States, residing at Detroit, in the county of Wayne and State of Michigan, have invented a new, original, and ornamental Design for a Vehicle-Body, of which the following is a specification, reference being had to the accompanying drawing, forming part thereof.

The figure is a side elevation of the vehicle body showing my design.

I claim:

The ornamental design for a vehicle body, as shown.

ADRIAN J. NEERKEN.

Witnesses:

H. B. KNAP,
LE ROI J. WILLIAMS.
